3,370,735 COLLAPSIBLE CONTAINER

David J. Wyrough, Roxboro, N.C., assignor to Midland-Ross Corporation, Cleveland, Ohio, a corporation of Ohio

Filed Oct. 20, 1965, Ser. No. 498,883
8 Claims. (Cl. 217—12)

ABSTRACT OF THE DISCLOSURE

A so-called "knock-down" shipping container which is rigid in assembled form and collapsible into a flat "return" package characterized by separable side walls, and corner members which provide leg structure adapting the container for fork-lift truck handling, and an unfastened floor which seats internally the side walls at the upper ends of the leg structure. The container is held in assembled relationship about the floor by steel straps or other flexible tie means extending horizontally around the aforementioned components.

Many types of lading require careful packaging and well-constructed containers. As the demand for sturdiness increases the cost of packaging, a cost level is reached at which it may be economical to return shipping containers, especially, if they are susceptible to disassembly into a return package of relatively small volume. The utility of such containers may arise also to a substantial degree through capability of being stored in collapsed condition near the location where they are to be loaded. Hence, where there is extensive in-plant use of containers that do not enter commercial shipping channels, the economy of storage achieved through the use of collapsible or "knock-down" containers may warrant their use. Furthermore, as the cost of packaging is included in the taxable base of products entering some foreign countries, returnable containers reduce the valuation of lading subject to, e.g., tariffs.

Hence, an important object of this invention is to provide a container having a rigid configuration in the assembled condition, but capable of being collapsed and reduced to a package of small volume relative to its bulk in assembled condition.

Another object is to provide a "knock-down" container in accordance with the above object of a design permitting the use of lightweight and high-strength materials.

A further object is to provide a "knock-down" container having its undersurface accessible to lifting implements, such as forklift trucks, crane cables, and the like.

Still another object is to provide a collapsible container which interlocks into a unit highly resistant to accidental disassembly regardless of the position.

The above objects and any others apparent hereinbelow are achieved in a collapsible box or container having a plurality of rigid side-wall members, a like number of elongate corner members having reentrant means for receiving edge portions of the side wall members, floor means such as a specially shaped floor adapted to fit the inner periphery of the box as formed by the members when joined together, and support means such as shelf members or other upwardly-facing abutment structure on the side wall members and/or the corner members to support the floor in a desired plane above a supporting surface for the box or container. The corner members include legs which space the floor means above any surface for supporting the container. The container further includes flexible strap means, such as metal bands disposed tautly around the members when the container is assembled.

In the drawing with respect to which this invention is described below,

2

FIG. 1 is a perspective view of one embodiment of the invention shown with a portion of one side-wall broken away to expose the floor member thereof.

5 FIG. 2 is a fragmentary plan view with a floor member portion broken away of a portion of the box shown in FIG. 1.

FIG. 3 is a perspective view of another embodiment having modified corner members.

10 FIG. 4 is a fragmentary plan view of a corner portion of the container of FIG. 3 with the floor member removed.

FIG. 5 is a fragmentary plan view with a portion of the floor member broken away of a portion of a modified box.

15 FIG. 6 is a fragmentary perspective view of portions of a side wall member and the floor member of a box such as shown in FIGS. 1 and 3 in abutting relationship.

FIGS. 7 and 8 are fragmentary perspective views of modified collapsible boxes or containers illustrating, in particular, modified corner members.

20 FIG. 9 is an exploded, fragmentary, perspective view of a corner portion of a collapsible container shown with the floor member omitted for clearer illustration of the corner member.

FIG. 10 is a fragmentary plan view of parts of the box 25 illustrated in FIG. 9 in assembled condition.

FIG. 11 is a fragmentary elevation in section of the box shown in FIGS. 9 and 10.

FIG. 12 is a perspective exploded view of a disassembled box shown arranged for parts being compacted.

30 FIG. 13 is an elevation view of the disassembled box of FIG. 12 compacted as when stored or placed in shipment.

FIG. 14 is a perspective view of the container of FIGS. 9 to 13 in combination with a lid therefor.

35 Considering now the various embodiments of the invention in detail, one form of knock-down box is shown in FIGS. 1 and 2. Box 4 comprises, as major components, four rigid side wall members 5, 6, 7, and 8; four corner members 11, 12, 13, and 14 in alternate relation with the side wall members; a floor member 16; and straps 17, 18, and 19. The bottom leg extensions of the corner members characterize the box as one adapted for lifting by fork-truck or other implement capable of reaching underneath the box.

40 FIG. 2 is a plan view of a corner portion of the box 4 which is typical of any one of its other three corner portions. This figure, in conjunction with FIG. 1, illustrates the construction of the corner members 11 to 14. As shown, each corner member comprises, essentially, a single sheet of material bent along a dihedral angle agreeing with the angle between corresponding side wall members received by the corner member into two side portions 21 and 22. Each side portion comprises an edge section which has been cut along a plurality of parallel lines from the extreme edge of each portion inwardly toward the apex or corner at which portions 21 and 22 join by shaping procedures well-known to form sets of alternate tabs in dispersed and longitudinally and transversely spaced relationship. One set of alternate tabs in each side portion, i.e., sets of tabs 23 and 24, are shown shaped to an L-contour with respect to the remainder of the respective side portions 21 and 22. This disposes tabs 23 and 24 in outward, parallel, spaced relation with the plane containing the unbent tabs, e.g., sets of tabs 27 and 28.

45 This arrangement of tabs constitutes one form of reentrant means for receiving edge portions of the side members as featured in this invention. The tabs may be provided with additional means for retaining the side members as a feature of this invention. The tabs may be provided with additional means for retaining the side members within the reentrant region defined by, e.g., the

sets of tabs 23 and 24, by means such as snag teeth 31, 32. As a preference, a side member may be secured to a corner member more positively, as by teeth 31, 32, along one side portion of the corner member when it is desired to have the corner member and readily detachable from the other member as the drawing shows attached permanently to one side member. In practice, the prevention of loss of box components is thought to be better accomplished through a series of shipping trips involving knock-down operations by permanently affixing each corner member to one side member.

FIG. 2 illustrates a shelf or abutment portion 34, such as disposed in each of the legs of the corner members, which enable the four legs of the box collectively to add substantially to the load-supporting capacity of the box over a desired service period. In the particular embodiment of FIGS. 1 and 2, each of the side wall members 5, 6, 7, and 8 comprises a shelf or ledge piece, such as shelves 35 and 36 of side wall members 5 and 6, respectively. The floor member 16 rests upon these shelves (see also FIG. 5). The latter in turn rest upon upward-facing abutments in the leg portions of the corner members, e.g., the abutment 34 of leg 13. As indicated earlier herein, the floor member conforms approximately with the inner periphery of the side wall members at the desired floor plane. As shown in FIG. 6, it may be necessary to notch the shelf 35, as at 38, in order that the tab nearest the abutment 34 may be inserted between the side wall and the shelf secured thereto.

Strap means, such as the bands 17, 18, and 19, extend completely around the outer periphery of the box in transverse relation to the lengths of the corner members and maintain the box in assembled condition. These bands are applied in a manner used extensively in other types of packaging familiar to the shipping departments of most corporate manufacturers. Conventionally, these bands are applied by a portable implement which contains a supply roll of steel band and is capable of drawing and securing the band in a taut condition.

FIG. 4 is a view from overhead of a corner section of a modified container shown in FIG. 3 with the floor member omitted. This embodiment differs from that shown in FIGS. 1 and 2 in that only one side portion 21a has an edge section cut to form tabs 41 and 42. A further distinction is that the set of tabs, e.g., tab 41, are folded inwardly of the general planes of the side portions 21a and 22a. This arrangement disposes tab portion 43 of tab 41 in parallel spaced relation with the entire side portion 22a of the corner member 11a. Tab portion 43 is spaced from the side portion 22a to receive the side wall 45 of the side wall member 6a. Side wall member 5a, on the other hand, is received between the tabs 41 and 42 and permanently secured thereto by rivets such as rivet 46. The side wall members 5a and 6a include also the shelves 35a and 36a, shown with small edge portions disposed under the closest tab 41. The bottom of the corner member 11a is shown closed-off by a shelf 48.

FIG. 5 views from overhead the corner section of a modified collapsible container or box 4b wherein the corner section 11b is initially cut for tab formation in substantially the same manner as corner members 11 to 14 of FIGS. 1 and 2. However, two sets of L-shaped tabs, e.g., tabs 51 and 52, are formed inwardly of the dihedral angle between the main planes of the side portions 21b and 22b. The tabs 51 and 52 are in parallel spaced relation with corresponding sets of straight tabs, i.e., tabs 53 and 54, respectively. The latter tabs are shown unbent and in the main planes of the corner member side portions. The spaced sets of tabs thus provide the reentrant means in the corner member needed for receiving the side wall members 5b and 6b.

The container corner portion illustrated in FIG. 7 is illustrated primarily to depict another mode of constructing a corner member. The corner member 11c shown therein comprises a pair of thin sheets 55, 56, bent into

general conformity with the dihedral angle between the side wall members 5c and 6c. As shown, the inner sheet 56 is bent or otherwise formed with its edge portions 57 and 58 in spaced relation with edge portions 61 and 62 of the sheet 55 to provide the necessary reentrant means of the corner member for receiving the adjacent side wall members 5c and 6c. The sheets 55 and 56 are joined together as by welding, riveting, or bonding with an adhesive such as an epoxy-resin.

In FIG. 8 the corner member 11d receiving the side wall members 5d and 6d is typical of extrusions commercially available from extruders of metal and plastic materials. The corner member 11d comprises side portions 21d and 22d, each of which branches or becomes bifurcate in cross section proceeding in a direction away from the apex formed at the juncture of sections 21d and 22d.

FIGS. 9, 10, and 11 illustrate a further embodiment. The knock-down box 4e of these figures comprises corner members 5e and 6e, the corner member 11e, and the floor member 16e. For purposes of illustration, the floor member is omitted from FIG. 9 which illustrates a corner portion of the container with parts in abnormally detached relationship. Of particular interest is the construction of the corner member 11e. As shown, it is formed of three pieces of sheet material, such as steel or aluminum, in a desired configuration, viz., an angle element 65 formed as shown to a right dihedral angle, an elongate Z-shaped element 66 coextending with a major portion of the element 65 to form reentrant means for the side members 5e, 6e, and a generally U-shaped element 67 welded or otherwise secured in the usually lower end portion of the element 65. The cross-sectional shape of the Z-element is such that when a flat longitudinal section 69 thereof is welded or otherwise attached to side portion 21e of the element 65, cavities of a width a little larger than the thickness of the respective side wall edge portions are formed at 71 and 72. The side wall edge portions of members 5e and 6e are shown within these cavities. FIGS. 10 and 11 disclose that the shelves 35e and 36e of side wall members 5e and 6e, respectively, rest upon the top surface 74 of the U-shaped element 67. Thus, the element 67, secured as by spot welding of its tabs 75, 76, 77 to the element 65, provides reinforcement of the leg portion of the corner member and a shelf surface on which the side wall members may be located and supported. The element 67 is further of primary support for lading placed in the box 4e since the weight of the lading is transmitted from its floor member 16e thereto through the shelves 35e, 36e.

Preferably, the side wall member 5e is permanently attached to the corner member 11e by any of the means hereinbefore disclosed. An additional satisfactory means of attachment is by an adhesive, such as epoxy-resin applied liberally to the cavity 71 before insertion of the edge of the side wall member 5e.

The lower end of the element 66 is spaced sufficiently from the surface 74 of element 67 to permit disposition therebetween, in addition to the shelf member 35e, of an edge portion of the floor member 16e. The object of this arrangement is to secure the floor member in its position adjacent the surfaces of all of the corner members corresponding to surface 74. The floor member 16e may actually engage the side wall members 5e and 6e, as shown in FIGS. 10 and 11, to contribute to the rigidity of the assembled container. While the floor member is intended to extend under the entire end surface of web 79, this web of the Z-element 66 is formed with an outwardly projecting crimp or ridge 80 which positively overhangs the floor member. As shown, the shelves 35e and 36e have beveled end surfaces in abutting relationship over the element 67.

The components of box 4e are held together in the same manner as illustrated in FIGS. 1 and 4 by flexible bands encompassing the periphery of the box, such as bands 17, 18, and 19.

FIGS. 12 and 13 illustrate, for example, the box in FIGS. 9, 10, and 11 in a disassembled condition exemplary of the collapsed condition that can be achieved by the embodiments of this invention to effect a neat, compact package of the container components suitable for storage or return from a delivery point of lading carried therein.

FIG. 12 is an exploded view of the package of box components shown placed one on top of the other in FIG. 13. From FIG. 12 it is apparent that for easier packaging, the floor member 16e is divided into two relatively hinged sections; side wall member 5e is attached to the corner member 11e, the side wall member 6e is attached to the corner member 12e, and so on.

If further compactness in packaging is required, the box may be constructed with the corner members and side wall members readily separable so that the plate-like side wall members and the floor member may be grouped in one bundle and the corner members formed into another bundle. However, because of the tendency in practice of the side wall members to stray into other uses, it is generally preferable to integralize one side wall member with one corner member.

FIG. 14 illustrates that any of the knock-down boxes herein disclosed, e.g., box 4e, may comprise a lid 85 having a top plate 86 and positioning means, such as molding 87 adapted to fit within the periphery of the top edges of the side walls of the box. The lid 85 may be secured in transit by the means shown, i.e., straps 88 and 89 passing over and under the box, shown in loose condition but used in taut condition in the manner of the horizontal straps 17, 18, and 19.

The embodiments hereinabove described disclose an arrangement of container components which unite into a highly practical collapsible container not heretofore commercially available. It is of a design adapting it for heavy duty service and handling by the various lifting implements used in the shipping industry.

The terms and expressions which have been employed are used at terms of description and not of limitation and there is no intention of excluding such equivalents of the invention described or portions thereof as fall within the scope of the claims.

That which is claimed is:

1. A knock-down box defining an inner periphery along a desired floor plane comprising in assembled condition: a plurality of side wall members disposed in serial edge-to-edge arrangement along said periphery; a like number of elongate corner members in alternate relation with the side wall members, each corner member comprising reentrant means extending along both planes of a dihedral angle extending lengthwise of the corner member having received therein edge portions of side members disposed in said angle planes with at least one edge portion readily separable from a corner member to render the box collapsible; floor means having an outer periphery conforming approximately to said inner periphery and disposed in engageable relation with the inner sides of the wall members, said floor means cooperating with the side members to form the bottom side of the container; support means comprising a leg forming a lower portion of each corner member, each leg having an upward-facing abutment for supporting said side wall members and said floor means in said floor plane; and flexible strap means secured around said members in taut condition and in transverse relation to the lengths of said corner members to maintain the box in assembled condition.

2. The knock-down box of claim 1 wherein said support means further comprises a shelf fixed to each wall

member having a support surface approximately in said plane and extending inwardly of said inner periphery for receiving said floor means.

3. The knock-down box of claim 1 wherein each wall member having a shelf secured on its inner side along its bottom edge for receiving said floor means extending into superposed supported relation with said abutments.

4. The knock-down box of claim 1 wherein: said corner member comprises substantially a single sheet of material having two side portions, each portion is disposed generally in one plane of said dihedral angle, at least one of said portions has an outer marginal section cut from its outward edge toward the apex of said angle to divide said section into a plurality of tabs; and

said reentrant means comprises two sets of said tabs along said cut section of which one set is dispersed within the other set and bent in relation to the other set to receive an edge of a side member between said two sets.

5. The knock-down box of claim 1 wherein: said reentrant means terminates just short of a plane occupied by the surface of the floor means which faces lengthwise of the reentrant means, and the floor means extends into facing relation with an end surface of the reentrant means to thereby lock the floor means into place in the assembled box.

6. The knock-down box of claim 1 wherein: said corner member comprises two elongate elements of sheet material secured back-to-back in general conformity with said dihedral angle; and said reentrant means comprises edge portions of the elements extending lengthwise of the member and separated to receive therebetween edge portions of said side wall members.

7. The knock-down box of claim 1 wherein said corner member comprises an angle element and a Z-element of sheet material, said angle element is of angular cross-section having two side portions conforming to planes of a dihedral angle, and the Z-element is of Z-cross section and secured along an inward surface of one side portion of the angle element with a longitudinal edge section in spaced relation with an edge section of the angle element to provide said reentrant means for both side members received by the corner member.

8. The knock-down box of claim 1 wherein at least one of said corner members comprises an angle element having side portions conforming to the planes of a dihedral angle and, for forming said leg, said member comprises an element of sheet material shaped generally to U-shape configuration secured in said leg, said U-shape element having side sections secured adjacent their termini to one of said portions of the angle member, and a middle section which connects the side sections secured to the other of said side portions.

CERTIFICATE OF CORRECTION

Patent No. 3,370,735

February 27, 1968

David J. Wyrough

It is certified that error appears in the above identified patent and that said Letters Patent are hereby corrected as shown below:

Column 3, lines 5 and 6, "to have the corner member and readily detachable from the other member as the drawing shows attached permanently to one side member" should read -- to have the corner member attached permanently to one side member and readily detachable from the other member as the drawing shows --.

Signed and sealed this 10th day of March 1970.
